UNITED STATES PATENT OFFICE.

JOHN MAY, OF LONDON, ENGLAND.

KNIFE.

SPECIFICATION forming part of Letters Patent No. 492,409, dated February 28, 1893.

Application filed November 19, 1892. Serial No. 452,482. (No model.) Patented in England January 14, 1892, No. 787.

To all whom it may concern:

Be it known that I, JOHN MAY, a subject of the Queen of Great Britain, and a resident of Penhurst, London, in the county of Kent, England, have invented certain new and useful Improvements in Finger-Guards for Table-Knives, (for which I have obtained a patent in Great Britain, No. 787, dated January 14, 1892,) of which the following is a full, clear, and exact specification.

My invention relates to an improved finger support, rest, or guard for table or other knives and consists of a padded clip of any suitable shape and material padded or cushioned upon the inside and outside bearing surfaces with indiarubber felt or the like.

For example I provide a piece of steel or other material a about one inch, more or less long which I bend into a shape so as to clip the back of the knife c . Upon the two inside bearing surfaces of the clip a , likewise the top, I provide cushions of indiarubber or felt or other soft material d and b . The finger it will be understood rests or bears upon the said flat top of the clip a on cushion b attached to the back of knife c and so protects the finger from injury. The clip a may be made to form an ornamentation as well as a protection to the finger.

What I claim, and desire to secure by Letters Patent, is—

In finger guards for knives a clip a provided with a cushion b and rubber bearing surfaces d in combination with the back of the knife, substantially as described.

In testimony that I claim the foregoing I have hereunto set my hand this 30th day of September, 1892.

JOHN MAY.
